UNITED STATES PATENT OFFICE.

GEORGE F. EPPLEY, OF WASHINGTON, DISTRICT OF COLUMBIA.

FORM CLAMP.

Application filed June 27, 1927. Serial No. 201,783.

This invention relates to a clamp designed primarily for use in connection with the forms of concrete columns utilized in building constructions and it is more particularly 5 an improvement upon the clamp disclosed in my co-pending application filed January 8, 1927, Serial No. 159,903.

It is an object of the present invention to simplify and reduce the cost of construction by eliminating some of the metal heretofore required, the changed or improved construction resulting not only in a lighter and less expensive clamp but also in a clamp the parts of which can be more quickly assembled and separated than heretofore.

A further object is to provide a clamp each member of which is adapted to be hooked over the next adjoining member, thereby enabling the parts to be assembled 20 without the necessitating of slipping one of them over the end of the other.

With the foregoing and other objects in view which will appear as the description proceeds, the invention resides in the combination and arrangement of parts and the details of construction hereinafter described and claimed, it being understood that changes in the precise embodiment of the invention herein disclosed may be made 30 within the scope of what is claimed, without departing from the spirit of the invention.

In the accompanying drawings, the preferred form of the invention has been shown.

In said drawings,

Figure 1 is a section through a column and form showing the improved clamp assembled therewith.

Figure 2 is an edge view of one of the clamp members.

Figure 3 is a section on line 3—3, Figure 2.

Referring to the figures by characters of reference 1 designates a flat bar having ratchet teeth 2 along one edge thereof adjacent one end while the other end portion of the bar is bent upon itself to provide a hook 3 the opening in which is of a width slightly greater than the thickness of the bar. A pawl 4 is pivotally mounted within 45 and extends in opposite directions from the hook, one end of the pawl being adapted to engage the teeth of a second bar when positioned within the hook. The bar 1 is offset at an intermediate point as shown at 5 so that the longitudinal center of the opening 55 in the hook 3 will be in line with the longitudi-

dinal center of the far end portion of said bar. This will be clearly apparent by referring to Figure 2 wherein the center line has been indicated at 6.

In practice the form F is set up and one of the clamp members is arranged along the outer surface of each side thereof. The clamp members are assembled by hooking each of them into engagement with the next 60 adjoining member. This can be done without slipping the hook over the end of the engaged member. Accordingly should the end of one of the members come against an adjacent wall, the proper assembly of the 65 parts would not be interfered with. As noted in Figure 2 the distance between the hook 3 and the offset portion 5 is slightly greater than the width of a bar so that it is thus possible readily to insert a bar into 70 engagement with a hook. After the members or bars have been assembled they can be tightened by shifting each bar longitudinally to move one or more of its teeth past the tooth engaging end of the adjacent pawl. 75 This pawl, by engaging one of the teeth, will hold the bar against retrograde movement and thus, after the several bars have been properly tightened the parts of the form will be held tightly together. Any suitable 80 means can be employed for tightening the bars. After the column has been poured and set the clamp can be removed readily 85 simply by disengaging the pawls from the teeth whereupon the parts can be quickly 90 loosened and unhooked.

Importance is attached to the one-piece construction of each bar whereby cost of production is materially reduced. The use of a hook is also important for the reasons heretofore pointed out and by having the offset in the bar the line of force is maintained directly through the center of the hook and of the toothed portion of the bar so that the bar will not become distorted when subjected 95 to excessive strain.

What is claimed is:

1. A form clamp comprising a plurality of interfitting members each including a flat bar having ratchet teeth along one longitudinal edge adjacent one end, a bar embracing hook at its other end, and a ratchet engaging pawl pivoted in the hook.

2. A form clamp comprising a plurality of interfitting members each including a flat bar having a hook at one end and a longitudinal series of ratchet teeth at its other

end, said bar being formed in a single piece, and a pawl pivoted within the hook, said hook constituting means for receiving a bar to be engaged by the pawl.

5. 3. A form clamp comprising a plurality of interfitting members each including a flat bar having one end bent upon itself to provide a hook, there being ratchet teeth extending longitudinally of the other end portion 10 of the bar, said bar being movable transversely of another bar to position the hook in

engagement therewith, a pawl pivotally mounted within the hook for engagement with the engaged bar, there being an offset in the bar between the hook and the teeth whereby the center line of force is extended longitudinally of the center of the hook and of the toothed portion of the bar. 15

In testimony that I claim the foregoing as my own, I have hereto affixed my signature. 20

GEORGE F. EPPELEY.
